LIGHTING CONTROL APPARATUS

George R. Pflasterer, Swissvale, Pa., assignor to
The Union Switch & Signal Company, Swiss-
vale, Pa., a corporation of Pennsylvania

Application March 16, 1937, Serial No. 131,141

5 Claims. (Cl. 246—3)

My invention relates to lighting control apparatus, and is particularly adapted for, though in no way limited to, the floodlighting of manually operable railway track switches. More specifically, it relates to means for illuminating at night a hand-operated railway track switch and the area adjacent the switch so that the manipulation and inspection of the switch and associated apparatus after dark will be expedited and so that the hazards which may be involved in such manipulation and inspection will be minimized.

I will describe two forms of apparatus embodying my invention, and will then point out the novel features thereof in claims.

15 In the accompanying drawing, Fig. 1 is a dia-
grammatic view illustrating one form of apparatus embodying my invention. Fig. 2 is a dia-
grammatic view illustrating a modification of a portion of the apparatus shown in Fig. 1 and also embodying my invention.

20 Referring to Fig. 1, the reference character W designates a railway track switch of the well-known dual control type. That is, the switch W can be operated by a power mechanism M or a manually operable lever H in accordance with 25 the position of link 1. For controlling link 1, I provide a selector lever S which has a normal or left-hand position and a reverse or right-hand position. The selector lever S also controls a 30 contact 2. When the selector lever S is in its normal position, link 1 connects switch W with mechanism M and engages contact 2 with contact 3 whereas, when selector lever S occupies its reverse position, link 1 connects switch W to hand-throw lever H and engages contact 2 with contact 4.

35 For illuminating the switch S and the area adjacent the switch, I provide a lamp F which is preferably of the floodlight type. For controlling the lamp F, I provide a control relay R. That is, when the relay R is energized, a circuit will be completed for lamp F over a path which passes from terminal B of a suitable source of energy through front contact 5 of relay R and lamp F to terminal C of the same source of energy.

40 For controlling the relay R in cooperation with contact 2, I provide a slow acting device TE and a light sensitive device P. The slow acting device TE is here shown as a thermal relay having a slow pick-up characteristic. The light sensitive device P, as here shown, comprises a photoelectric generator X exposed to the atmosphere adjacent the switch W and an auxiliary relay XR connected to the generator X. The generator X has 45 a property of converting the energy of light rays

into electrical energy. A number of such photoelectric generators are well-known, one such generator being described in United States Letters Patent No. 1,970,135, issued August 14, 1934, to Lars O. Grondahl and Paul H. Geiger. When 5 the amount of daylight adjacent the switch W is above a predetermined value, the generator X will generate sufficient current to pick up the relay XR whereas, when the amount of daylight decreases below this predetermined value, the generator X will not supply sufficient current to maintain relay XR in its picked up condition.

Assuming that selector lever S is moved to its reverse position to condition the switch W for manual operation when the relay XR is released, 15 that is, after dark, it will be apparent that the control relay R will be energized by a circuit which passes from terminal B through contact 2—4, back contact 6 of relay XR, and relay R to terminal C. The picking up of relay R will, of course, energize floodlight F over front contact 5 of relay R so that the switch and the area adjacent the switch will be illuminated. When, however, the selector lever S is restored to its normal position, the relay R will not become released immediately because of a stick circuit which passes from terminal B through back contact 7 of thermal relay TE, front contact 8 of relay R, and relay R to terminal C. This feature insures that the floodlight F will remain lighted for a given 20 interval of time after the switch is restored to its initial condition so that the switch and associated apparatus may be properly inspected. When contact 2 is in engagement with contact 3 and relay R is picked up, a circuit will be established for thermal relay TE which circuit passes from terminal B through contact 2—3, front contact 9 of relay R, and thermal relay TE to terminal C. At the expiration of a given time interval when relay TE completes its operation, back contact 7 of relay TE will become open to release relay R so that floodlight F will be extinguished.

45 Referring now to Fig. 2, the reference character 10 designates a padlock operated contact which is controlled in such a manner that when the switch is properly locked by the insertion of the usual switch padlock, (not shown) in its keeper (not shown) the contact 10 will be in engagement with contact 11 whereas, when the padlock is withdrawn from its keeper to condition 50 the switch for manipulation, the contact 10 will be in engagement with contact 12. It will be apparent that, contact 10 can be substituted for contact 2 to control the floodlight F in a manner similar to that just described for the appara- 55

tus shown in Fig. 1. In other words, when the switch is unlocked to permit manual operation, the floodlight F will become energized and will remain energized for a given interval of time after the switch is restored to its locked condition. The padlock operated contact shown in Fig. 2 may be operated by the padlock usually applied to an ordinary hand-throw switch or may be controlled by a padlock which locks selector lever S. The mechanism for operating contact 10 is not shown because such mechanisms are well-known. One form of mechanism for operating a padlock contact is shown in United States Letters Patent No. 2,042,873 granted to Paul F. Willard, June 2, 1936, for Railway traffic controlling apparatus.

Although I have herein shown and described only two forms of apparatus embodying my invention, it is understood that various changes and modifications may be made therein within the scope of the appended claims without departing from the spirit and scope of my invention.

Having thus described my invention, what I claim is:

- 25 1. In combination, a railway track switch, means for conditioning the switch for power operation or manual operation, a floodlight for illuminating the switch and the area adjacent the switch, a control relay effective when picked up to energize said floodlight, means effective if the amount of daylight is below a predetermined value to pick up said control relay when said switch is conditioned for manual operation, a slow pick-up relay, means including a back contact of said slow pick-up relay for maintaining said control relay in its picked up condition, and means effective when said control relay is picked up and said switch is in condition for power operation to energize said slow pick-up relay.
- 40 2. In combination with a dual controlled railway track switch, a first contact which is closed when said switch is in condition for power operation and a second contact which is closed when said switch is in condition for manual operation, a photoelectric generator exposed to daylight adjacent said switch, an auxiliary relay which becomes picked up or released according as the amount of daylight received by said photoelectric generator is above or below respectively a given value, a control relay, means for energizing said control relay including said second contact and a back contact of said auxiliary relay, a slow acting device having a contact which is closed when said device is in its initial condition but which becomes opened when said device attains its operated condition, means including said contact of the slow acting device and a front contact of said control relay for maintaining the control relay in its picked up condition, means including said first contact and a front contact of said control relay for initiating the operation of said device, a floodlight for illuminating said switch, and means including a front contact of said control relay for energizing said floodlight.
- 65 3. In combination with a dual controlled railway track switch, a first contact which is closed when

said switch is in condition for power operation and a second contact which is closed when said switch is in condition for manual operation, a photoelectric generator exposed to daylight adjacent said switch, an auxiliary relay which becomes picked up or released according as the amount of daylight received by said photoelectric generator is above or below respectively a given value, a control relay, means for energizing said control relay including said second contact and a back contact of said auxiliary relay, a normally deenergized slow pick-up relay, means including a back contact of said slow pick-up relay and a front contact of said control relay for maintaining the control relay in its picked up condition, a circuit for energizing said slow pick-up relay including said first contact and a front contact of said control relay, and a floodlight for illuminating the switch governed by said control relay.

4. In combination, a railway track switch, a floodlight for illuminating the railway track switch, a control relay operative when energized to supply current to said floodlamp, a member movable between a normal and an operated position for controlling said switch, photosensitive means responsive to the amount of daylight at said switch, a pick-up circuit controlled by said member and said photosensitive means for supplying current to energize said control relay, a stick circuit controlled by said control relay for also supplying current to energize said control relay, and means controlled by said control relay and by said member for also controlling said stick circuit, said means being operative to interrupt said stick circuit only after a predetermined time interval after movement of said member to one of its positions.

5. In combination, a railway track switch, a dual selector lever having a normal position in which it conditions the switch for power operation and having a hand-throw position in which it conditions the switch for manual operation, a floodlamp for illuminating the switch, a control relay operative when energized to establish a circuit for supplying current to the floodlamp, photosensitive means responsive to the amount of daylight at said switch, a pick-up circuit for supplying current to energize said control relay, the pick-up circuit being controlled by the photosensitive means and by the selector lever and being complete when and only when the selector lever is in the hand-throw position and the daylight at said switch is less than a predetermined value, a stick circuit for supplying current to energize said control relay, said stick circuit being established on energization of the control relay, a timing device operative a predetermined time interval after the supply of current thereto to interrupt the stick circuit for the control relay, and a circuit for supplying current to said timing device, said last-named circuit being complete when and only when the control relay is energized and the selector lever is in the normal position.

GEORGE R. PFLASTERER.
